J. FARMER

MANUFACTURE OF TWIST LACE NET

Filed July 12, 1922

Inventor
James Farmer.
by Robert W. Jenner.
Attorney.

UNITED STATES PATENT OFFICE.

JAMES FARMER, OF NOTTINGHAM, ENGLAND.

MANUFACTURE OF TWIST-LACE NET.

Application filed July 12, 1922. Serial No. 574,367.

To all whom it may concern:

Be it known that I, JAMES FARMER, a subject of the King of Great Britain, and a resident of the city and county of the city of Nottingham, in England, have invented certain new and useful Improvements in the Manufacture of Twist-Lace Net, of which the following is a specification.

This invention relates to improvements 10 in the manufacture of twist-lace traverse net, on what are known as plain net machines, in which the carriages are arranged in two tiers one of which is traversed in the reverse direction to the other. Its object is to produce what is known as a "filet" 15 net, that is a net with a square mesh.

According to this invention, the vertical bars of the net are comprised of two bobbin threads and two warp threads twisted together, one warp thread being twisted in the reverse direction to the other, whilst the horizontal bars are formed by two bobbin threads, one of which is carried from left to right, and the other from right to left.

25 The accompanying drawing is a diagram showing the disposition of the threads, in a twist-lace traverse net with a square mesh made according to our invention.

In producing this net, a full set of warp 30 threads is employed in the machine, but it is divided into two half sets A and B, one of which half sets A is comprised of right and the other set B of reverse twist threads.

Each half set of warp-threads is controlled 35 by a separate and distinct thread guide-bar, there are therefore two of the latter, one being disposed at the back of the other, and their traversing movements are as follows:—

40 When both tiers of carriages are in the front comb-bar, one the back guide-bar which controls the reverse twist warp threads B, traverses one gate or carriage space to the left, and the other front guide-bar which 45 controls the right twist warp threads A traverses one gate or carriage space to the right. When both tiers of carriages are in the back comb-bar, both thread guide-bars return to their initial positions again. When 50 one tier of carriages is in the front comb-bar and the other tier is in the back comb-bar (intermediate position) both thread guide-bars stand.

55 The result of this action is that pairs of warp-threads, that is, the corresponding threads in each half set A, and B, twist

with pairs of bobbin threads C, that is, the threads of the corresponding carriages in the front and back tiers.

In order to form the horizontal bars of 60 the net, the front comb-bar is shogged or traversed at the required regular intervals, that is, every four, six, eight or more motions of the machine as follows:—

When both tiers of carriages are in the 65 front comb-bar, the latter moves to the left or falls one gate, and when during their movement into the back comb-bar, the back tier of carriages has moved into said back comb-bar whilst the front tier is still in the 70 front comb-bar, (intermediate position) the latter rises or moves to the right two gates.

As a result of this action, two ties are formed by the bobbin threads in one motion, one tie C' being formed by a bobbin thread 75 C traversing to the left, and the other C² by a bobbin thread C traversing to the right, both of which are nipped together by the warp threads, forming the double horizontal bars of the net, as previously de- 80 scribed.

The front comb-bar returns to its initial position again when both tiers of carriages are in the back comb-bar.

In order that the twist in the vertical bars 85 of the net may be evenly formed, the take-up of the work is effected by the point bars every motion of the machine, instead of at longer intervals as is more usual in this type of machine.

90 It will be understood that the same result would be obtained by reversing the traversing movement of the thread guide-bars and the front comb-bar.

In order to obviate the necessity for using 95 right and reverse twist warp threads as previously described, the twisting of the warp and bobbin threads may be reversed say every repeat, that is to say, the warp threads which twist one way in producing one repeat 100 of the net, twist the reverse way in making the next repeat. In this case the warp threads may be all right or all reverse twist threads.

105 The net may be also produced but perhaps not quite so perfectly, by traversing the front comb-bar in the following alternative manner. It falls one gate or carriage space when all the carriages are in the back comb-bar, rises one gate when the carriages 110 are in their intermediate position, falls one gate when the whole of the carriages are

in the front comb-bar, and rises one gate when the carriages are in their intermediate position again.

In this system of working the ties to the right and left are not formed on the same, but in successive motions of the machines.

What I claim as my invention and desire to secure by Letters Patent is:—

A twist lace traverse net with a square mesh in which the vertical bars are formed by two bobbin and two warp threads the

latter being twisted in reverse directions round the former and the horizontal bars are each formed by two bobbin threads one of which is traversing to the right and the other to the left throughout the net. 15

In witness whereof I have hereunto set my hand in the presence of two witnesses.

JAMES FARMER.
